UNITED STATES PATENT OFFICE.

HENRY H. FLECK AND JOHN G. FLECK, OF PHILADELPHIA, PENNSYLVANIA.

AUTOMATIC FLUSHING-TANK FOR WATER-CLOSET HOPPERS.

SPECIFICATION forming part of Letters Patent No. 784,784, dated March 14, 1905.

Application filed September 27, 1904. Serial No. 226,112.

To all whom it may concern:

Be it known that we, HENRY H. FLECK and JOHN G. FLECK, citizens of the United States, residing at the city of Philadelphia, in the 5 county of Philadelphia and State of Pennsylvania, have jointly invented certain new and useful Improvements in Automatic Flushing-Tanks for Water-Closet Hoppers, of which the following is a specification.

10 Our invention has relation to a flushing-tank for water-closet hoppers adapted to be automatically controlled by the depressing or elevating of the seat of the water-closet; and in such connection it relates particularly to the 15 construction and arrangement of such a flushing-tank for said purposes.

The principal objects of our invention are, first, to provide a flushing-tank for water-closet hoppers which shall be normally empty, 20 and especially as such at certain seasons anti-freezing, and, second, to provide in such a flushing-tank means for automatically filling the tank when a person is seated upon the hopper-seat and readily and quickly freed of 25 its fluid contents upon rising from the hopper-seat to thoroughly flush the same.

The nature, characteristic features, and scope of our invention will be more fully understood from the following description, taken 30 in connection with the accompanying drawings, forming part hereof, in which—

Figure 1 is a vertical central sectional view of a flushing-tank embodying main features of our invention. Fig. 2 is an enlarged sectional detail view of a portion of actuating devices of the elevated tank, and Fig. 3 is a perspective view showing a form of water-closet hopper with an elevated flushing-tank of our invention in application thereto and 40 also showing the manner of controlling the filling and discharge of the fluid of the flushing-tank by the action of the seat of the water-closet hopper.

Referring to the drawings, the flushing-tank 45 A is provided at its bottom with ordinary outlet and inlet nozzles *a* and *b*, to which the flush-pipe *a'* and supply-pipe *b'* are respectively suitably connected therewith. The inner end of the outlet-nozzle *a* is formed into 50 a valve-seat *a''*, above which is arranged a

plunger-valve pipe *a''*, provided at its lower end with a rubber gasket *a'*, so that when the pipe *a''* is lowered in a manner to be herein-after described there is formed in conjunction with the valve-seat *a''* a closure for the 55 outlet-nozzle *a* to the pipe *a'*, leading to the hoppers. The pipe *a''* is open at its upper end to form an overflow when the pipe is in its lowermost position within the tank to close the outlet-nozzle *a*, and this pipe *a''* is suspended, by 60 means of a chain *a'*, from a fulcrumed rock-arm *c*, and from the end of this arm *c*, by means of a link *b''*, is suspended a cap *b'*. This cap *b'* serves as a counterweight to normally raise the pipe *a''* to maintain open the outlet-nozzle *a*, and the cap *b'* fits over the end *b''* of 65 the inlet-nozzle *b*, projecting upward into the flushing-tank A. This end *b''* is provided with perforations *b''* to control the flow of water into the tank when the cap *b'* is ele- 70 vated into the position illustrated. When the cap *b'* is in the position shown in Fig. 1, the water-supply to the tank is cut off; but when water is being supplied to the tank the cap *b'* will be raised by the pressure of the water, 75 so that the cap occupies the position illustrated, for example, in Fig. 2. The lower end of the cap *b'* is made, preferably, bell shape, as at *b''*, so that when the cap *b'* is raised by the pressure of the water the bell- 80 shape portion of the cap will occupy a position opposite the openings *b''*, and thus serve to maintain the cap in its raised position. A set-screw *b''* serves in conjunction with a slot *b''* to limit the range of vertical movement of 85 the cap *b'*, as illustrated in Fig. 2. In Fig. 3 is shown one manner of controlling the water-supply by means of the seat *d* of the water-closet. A spring-controlled valve *b''*, of ordinary type, employed to supply running water 90 to the water-closet hopper when a person is seated upon the seat, is arranged in the supply-pipe *b'*, and this valve *b''* is actuated in the usual manner by means of a lug *d'*, projecting from the seat *d*.

The mode of operation of the flushing-tank A is as follows: The tank is normally empty. When a person sits upon the seat *d*, the valve *b''* will be actuated, and the pressure of the water will cause the cap *b'* to be raised and 100

- the plunger-valve pipe a^3 to be lowered to close the outlet-nozzle a to the flush-pipe a' , leading to the hopper of the water-closet. The water will now flow into the tank A so long as a person remains seated on the seat d of the closet. When, however, the person rises from the seat d , the water-supply through the pipe b' to the tank will be cut off by the valve b^{10} , and the pressure being thus shut off the cap b^2 will fall and raise the pipe a'' through the rock-arm c , and the water will then flow rapidly from the elevated tank A through the pipe a' to the water-closet hopper to flush the same. The particular advantage of such a flushing-tank adapted to be maintained normally empty is that at certain seasons of the year, as water never remains in the tank, freezing of water therein will thereby be prevented.
- Having thus described the nature and objects of our invention, what we claim as new, and desire to secure by Letters Patent, is—
1. In a flushing apparatus, the combination with an elevated tank, of a supply-pipe leading thereto, a valve slidably connected therewith and normally controlling the outlet therefrom, a flush-pipe leading from said tank, a valve connected with said flush-pipe, and means connecting said flush-pipe valve with said supply-pipe valve, the latter adapted to hold said flush-pipe valve normally in an inoperative position and to close the same by the pressure of fluid supplied to said tank.
  2. In a flushing apparatus, the combination with an elevated tank, of a supply-pipe leading thereto, a valve movably connected therewith, a flush-pipe leading from said tank, a valve connected with said flush-pipe, means connecting said flush-pipe valve with said supply-pipe valve, the latter adapted to close the flush-pipe valve when raised by the pressure of the fluid conducted through said supply-pipe to said tank.
  3. In a flushing apparatus, the combination with an elevated tank, of a supply-pipe leading thereto and provided with outlets, a valve movably connected therewith and adapted normally to close the outlets of said supply-pipe,

a flush-pipe leading from said tank, a valve connected therewith, means adapted to connect said flush-pipe valve with said supply-pipe valve to hold the same open, the supply-pipe valve adapted to close the flush-pipe valve when raised by the pressure of the fluid conducted to said tank and to permit said flush-pipe valve to open when the supply to said tank ceases.

4. In a flushing apparatus, the combination with an elevated tank, of a supply-pipe leading thereto, a flush-pipe leading from said tank, a closet-bowl seat with a movable valve controlled by the movement of said seat to permit fluid to enter said tank by actuation of said supply-pipe valve and to close at the same time the flush-pipe valve and then upon the raising of the seat and closing of its valve to open the flush-pipe valve to empty the tank into said closet-bowl, a combined valve and overflow governing the flush-pipe, means in movable connection with the supply-pipe in said tank, and means connecting said means with said flush-valve, substantially as and for the purposes specified.

5. In a flushing apparatus, the combination with an elevated tank, of a supply-pipe leading thereto, a flush-pipe leading therefrom, a closet-bowl to which the flush-pipe is connected, a movable seat on said bowl, a valve in the supply-pipe controlled by said seat, a combined valve and overflow governing the flush-pipe, a bell-shaped cap upon the extremity of the supply-pipe within the tank having a sliding movement thereon, means for limiting said sliding movement and a rocking lever connected to said cap and to said flush-valve, whereby the latter is operated by the former.

In testimony whereof we have hereunto set our signatures in the presence of two subscribing witnesses.
